Attorney

UNITED STATES PATENT OFFICE.

FRANK SIMANTZ, OF GRAND HAVEN, MICHIGAN.

WALL CONSTRUCTION.

1,398,402.

Specification of Letters Patent. Patented Nov. 29, 1921.

Application filed May 5, 1921. Serial No. 467,152.

To all whom it may concern:

Be it known that I, FRANK SIMANTZ, a citizen of the United States of America, residing at Grand Haven, in the county of Ottawa and State of Michigan, have invented certain new and useful Improvements in Wall Constructions, of which the following is a specification.

This invention relates to certain new and 10 useful improvements in wall construction and has particular reference to the construction of partition walls for dwellings and the like.

The primary object of the invention is to 15 provide a simple and inexpensive way of constructing partition walls whereby the same will be substantially non-sound conducting and have the properties of durability and the like which insure successful commercial use.

Other objects will become apparent as the 20 nature of the invention is better understood, and the same consists of the novel form, combination and arrangement of parts, hereinafter more fully described, shown in the accompanying drawings and claimed.

In the drawings, wherein like reference 25 characters designate corresponding parts throughout the several views.

30 Figure 1 is a fragmentary elevational view of a wall partially completed in accordance with the present invention.

Fig. 2 is a horizontal sectional view along line II—II of Fig. 1,

35 Fig. 3 is a fragmentary elevational view of the sound deadening fabric employed, and Fig. 4 is a horizontal sectional view taken upon line IV—IV of Fig. 3.

Referring more in detail to the several 40 views, the present invention contemplates the erection of the usual uprights or studding 5 at suitable intervals and extending upwardly from the floor 6, as well as connected by horizontal laths 7 to which is applied a primary coating of plaster as at 8 in the usual manner.

The improvement embodied in the present 45 invention is in placing parallel closely related bamboo stalks against the outer surface of the primary plaster coating 8 as at 9 and then applying a second coating of plaster as at 10 to cover the bamboo stalks, whereby a finished appearance is given to the wall and whereby the partition wall is 55 made substantially non-sound conducting. For convenience in positioning the bamboo

stalks and applying the same to the primary coating of plaster, they are connected in proper relation by means of twisted wire as at 11, thus making a sort of fabric which may be manufactured in sheet or roll form. The wire embraces each stalk and the opposite strands are twisted between adjacent pairs of stalks in the preferred embodiment of the invention as shown clearly in Figs. 3 60 and 4, and the pith or core of the stalk is preferably removed so that the bamboo stalks are hollow or provided with a clear bore as at 12. The bamboo stalk fabric is preferably applied by stapling through 65 the primary coating of plaster 8 into the laths 7 as at 13 and it is preferable to apply the sound deadening fabric in horizontally arranged strips which may be superposed to extend to the ceiling if necessary. 75

The layers of plaster are applied to the lathing, and the studding and lathing are erected in the ordinary and well known manner. It will thus be seen that a reinforced sound deadening partition is provided. 80

From the foregoing description, it is believed that the construction and manner of erecting a wall in accordance with the present invention as well as the advantages of 85 the same will be readily understood and appreciated by those skilled in the art.

Minor changes may be made in the invention without departing from the spirit and scope thereof as claimed. 90

What is claimed as new is:—

1. In a wall construction, the combination with upright studding members having laths connecting the same, and a primary layer of plaster applied to said laths, 95 of a sound deadening fabric applied to the outer surface of said primary layer of plaster, and a second layer of plaster applied to the primary layer of plaster and said sound deadening fabric whereby the latter is completely covered.

2. In a wall construction, the combination with upright studding members having laths connecting the same, and a primary layer of plaster applied to said laths, of 105 sound deadening bamboo stalks applied to the outer surface of said primary layer of plaster, and a second layer of plaster applied to the primary layer of plaster and to said stalks whereby the latter is completely 110 covered.

3. In a wall construction, the combination

with upright studding members having laths connecting the same, and a primary layer of plaster applied to said laths, of a sound deadening fabric applied to the outer surface of said primary layer of plaster, and a second layer of plaster applied to the primary layer of plaster and said sound deadening fabric whereby the latter is completely covered, said sound deadening fabric comprising parallel bamboo stalks connected in slightly spaced relation.

4. In a wall construction, the combination with upright studding members having laths connecting the same, and a primary layer of plaster applied to said laths, of a sound deadening fabric applied to the outer surface of said primary layer of plaster, and a second layer of plaster applied to the primary layer of plaster and said sound deadening fabric whereby the latter is completely covered, said sound deadening fabric comprising parallel bamboo stalks connected in slightly spaced relation, the connecting means for the stalks including wire bent

around the stalks and twisted between the 25 same.

5. In a wall construction, the combination with upright studding members having laths connecting the same, and a primary layer of plaster applied to said laths, of a sound deadening fabric applied to the outer surface of said primary layer of plaster, and a second layer of plaster applied to the primary layer of plaster and said sound deadening fabric whereby the latter is completely covered, 35 said sound deadening fabric comprising parallel bamboo stalks connected in slightly spaced relation, the connecting means for the stalks including wire bent around the stalks and twisted between the same, said 40 stalks being vertically arranged.

In testimony whereof I affix my signature in presence of two witnesses.

FRANK SIMANTZ.
